UNITED STATES PATENT OFFICE

2,146,103

COMBINED PARKING AND SHOW PLACE

Charles J. Williamson, Washington, D. C., assignor to Park-In-Theatres, Inc., Camden, N. J., a corporation of New Jersey

Application August 2, 1933, Serial No. 683,375

4 Claims. (Cl. 20—1.12)

My invention concerns combined automobile parking and show places such, for example, as outdoor theaters of the description forming the subject of United States Patent No. 1,909,537, issued May 16, 1933. By the invention of that patent spectators of an outdoor exhibition, such as a moving picture, may enjoy the performance while seated in their automobiles in what is, in effect, a parking space that provides the auditorium, so that at one stroke seating equipment is eliminated and parking difficulties or problems are solved and spectators may enter and leave the auditorium in their automobiles. An object of my invention is to provide a different and, as I consider, a more advantageous arrangement for the parked cars in the auditorium than the particular one shown and described in the aforesaid patent.

My invention consists in whatever is described by or is included within the terms or scope of the appended claims.

In the accompanying drawing I illustrate my invention as embodied in an outdoor motion picture theater for the purpose of convenient illustration and comparison with the outdoor motion picture arrangement shown and described in the aforesaid patent.

In such drawing—

Fig. 1 is a top plan view of enough of such outdoor theater equipment to illustrate one embodiment of my invention;

Fig. 2 is a section on the line 2—2 of Fig. 1;

Fig. 3 is a similar view of another embodiment of my invention;

Fig. 4 is a like view of another embodiment of my invention.

One feature of my invention is that it avoids the parked cars standing at an incline when stationed for occupants to see the spectacle, or show, or exhibition, while at the same time affording a clear view or vision of the show or exhibit to occupants of cars, in ranks or rows behind others. Another feature of my invention avoids the necessity for a right angle turn of cars moving to and from parking stations and enabling the turn to be at an obtuse angle and thereby economizing in parking space, or area, and without any sacrifice of satisfactory view of the picture, show, or spectacle.

Describing in detail what is shown in the drawing: a picture screen 10 is conventionally illustrated and since the theater shown is an outdoor theater the ground surface or area in the front is marked or laid off to provide automobile parking spaces 11, parallel and spaced apart pro-

gressively from the screen to the rear of the lot or plot of ground. And the parking spaces are separated sufficiently to provide a drive-way 12 between two adjacent parking spaces for the entrance and exit of automobiles and for movement to and from adjacent parking spaces so that they will front towards the screen and in close side by side formation in any one transversely extending parking space. The parking spaces and the alternating drive-ways, while preferably parallel with one another, extend in the direction of their length obliquely or at an incline to the plane of the screen 10 so that parked automobiles fronting on the screen will occupy a position not at right angles to the plane of the screen, but horizontally inclined, or oblique, and also at a similar inclination to the length of the parking space. This means that an automobile entering or leaving a parking space may turn in the adjacent drive-way at an obtuse angle and thus will require less space in which to make the turn for leaving the parking spot and therefore the adjacent drive-way may be narrower and thus ground surface or floor area may be most economically utilized. The parking spaces and the intervening drive-ways may be curved or they may extend in straight lines.

As best shown in Figs. 2 and 3 the parking surfaces are horizontal so that the cars when at rest are upon horizontal surfaces without any tendency to roll therefrom by gravity, and also with the advantage that the occupants of the cars are not on seats that incline downward with a tendency to slide therefrom and compelling a position of the body and the actions of muscles which are apt to result in fatigue or discomfort; and yet while the parked cars are on horizontal surfaces the parking surfaces successively further and further from the screen or stage or other place of exhibition are sufficiently high so that the occupants of a rear automobile may readily see past an automobile ahead and have a full view of the screen, stage or place of action of the performance.

As shown in Fig. 2 the elevation of parking spaces successively further and further from the screen or stage may be secured by an arrangement in which the intervening or alternate drive-ways incline downward and forward from a higher parking space to a lower one and the cars on such inclined drive-ways may readily and directly move to and from parking position. Or as shown in Fig. 3 a stepped arrangement may be used in which this drive-way and parking space may be on the same horizontal level but at heights 55

successively higher and higher progressively from the screen or stage. Of course, suitable barriers will be placed at the forward edge of the steps to prevent the accidental movement of cars 5 thereover and preferably barriers will be provided at the forward side of each parking space arrangement shown in Fig. 2 as a matter of safety as well as to define or locate parked cars properly.

The oblique position of the parked cars enables 10 the screen or stage to be viewed from the car sides, and indeed, the advantage of this sidewise outlook of the car occupants from the car parking spaces may be utilized by placing the cars lengthwise wholly parallel with the screen, or end to 15 end in a row, as shown in Fig. 4, with enough space between adjacent cars to allow ingress and egress of a car. This arrangement has the advantage of diminishing ground or surface required, and with the parking spaces level or horizontal, objectionable sidewise slant of cars would 20 not occur.

What I claim is:

1. A combined parking and exhibition arrangement comprising exhibition means with a 25 horizontally extended exhibition surface and alternating parking and driveways extending in the same general direction as such horizontally extending surface but at an acute angle thereto there being free passage for automobiles by forward movement thereof between drive and parking ways, the parking ways being adapted to receive automobiles placed adjacent to one another and facing the exhibition means, whereby automobiles passing from the driveway to parking 30 spaces side by side may make a turn at an obtuse angle and park obliquely with reference to the exhibition means.

2. A combined parking and exhibition arrangement comprising exhibition means and a plurality 35

of parking spaces adapted to receive automobiles disposed adjacent to one another and facing the exhibition means, such parking spaces being horizontal surfaces and successively higher progressively from the exhibition means, and driveways 5 for automobiles between adjacent parking spaces and, in each of which driveways between adjacent rows of parking spaces automobiles may safely move, each such driveways being immediately contiguous a horizontal parking space and 10 of a width to permit endwise movement of automobiles along the same and turning thereof into a selected parking space, and without contact of a parking automobile with one in a selected parking area, the driveway contiguous a parking space 15 inclining downwardly and generally forwardly relative to the exhibition means.

3. In a combined parking and exhibition arrangement comprising exhibition means, alternating parking and drive-ways spaced from the 20 exhibition means and extending at an acute angle with respect to the exhibition means, there being free passage for automobiles by forward movement of the latter between at least each drive-way and one parking way, each parking way being adapted to receive automobiles in side by side arrangement from at least one of its contiguous drive-ways with the automobiles facing in the general direction of the exhibition means, whereby automobiles passing from a drive-way 25 to parking spaces side by side may turn from the drive-way at an obtuse angle and park obliquely to the exhibition means.

4. In a combined parking and exhibition arrangement as set forth in claim 3 further characterized by the drive-ways being inclined downwardly and forwardly toward the exhibition means.

CHARLES J. WILLIAMSON.
